CLAIM

The ornamental design for a nonwoven fabric, as shown and described.

DESCRIPTION

FIG. 1 is a front perspective view of a nonwoven fabric, embodying the first embodiment of the new design;
FIG. 2 is plan front view of the nonwoven fabric of FIG. 1;
FIG. 3 is a right-side view of the nonwoven fabric of FIG. 1;

FIG. 4 is a top-side view of the nonwoven fabric of FIG. 1;
FIG. 5 is a bottom-side view of the nonwoven fabric of FIG. 1;

FIG. 6 is a front perspective view of a nonwoven fabric, embodying the second embodiment of the new design;
FIG. 7 is plan front view of the nonwoven fabric of FIG. 6;
FIG. 8 is a right-side view of the nonwoven fabric of FIG. 6;

FIG. 9 is a top-side view of the nonwoven fabric of FIG. 6;
and,

FIG. 10 is a bottom-side view of the nonwoven fabric of FIG. 6.

The broken lines in the figures form no part of the claimed design.

1 Claim, 8 Drawing Sheets
